(57) **CLAIM**

The ornamental design for an electrode arrangement for a portable cardiogram recorder, as shown and described.

DESCRIPTION

FIG. 1 is a front elevational view of one side of an electrode arrangement for a portable cardiogram recorder showing my new design;

FIG. 2 is a rear elevational view of the electrode arrangement shown in FIG. 1;

FIG. 3 is a side elevational view of the electrode arrangement shown in FIG. 1;

FIG. 4 is a side elevational view of other side of the electrode arrangement shown in FIG. 1;

FIG. 5 is a top plan view of the electrode arrangement shown in FIG. 1;

FIG. 6 is a bottom plan view of the electrode arrangement shown in FIG. 1; and,

FIG. 7 is a cross-sectional view of the portable cardiogram recorder shown in FIG. 1 taken along line 7—7 of FIG. 5., with the internal system omitted.

The broken line showing of a body of the portable cardiogram recorder in FIGS. 1—7, is for illustrative purposes only and forms no part of the claimed design.
